ROTARY FILLING MACHINE

William E. Gross, Joppa, Md.

Application April 21, 1949, Serial No. 88,874

3 Claims. (Cl. 226—97)

(Granted under Title 35, U. S. Code (1952),
sec. 266)

1

The invention described herein may be manufactured or used by or for the Government for governmental purposes without payment to me of any royalty thereon.

This invention relates to filling receptacles, more particularly to novel apparatus for automatically filling gas mask canisters of the axial flow type.

The primary object of the present invention is to provide a machine that will automatically deliver to a plurality of receptacles a charge of granular material, while maintaining uniform bulk-density of the charge delivered to each receptacle.

A supplementary object is to automatically, partially fill a receptacle to a predetermined depth below the top edge of the receptacle, and to concurrently maintain a uniformly level top surface of the charge delivered to the receptacle.

Additional objects will more plainly appear from the detailed specification and drawings herein presented in exemplification but not in limitation of the present invention. Like reference characters represent like parts in the accompanying drawings which diagrammatically illustrate a preferred embodiment of the present invention and wherein:

Fig. 1 represents a front elevation of the assembled machine.

Fig. 2 a plan view of the rotary drive for the table.

Fig. 3 a front elevation, partly in cross-section, of one of the filling tubes.

It is essential that an axial flow canister for gas masks be filled in a manner that meets the following requirements in order that the charge will not become channeled and consequently inoperative or hazardous when used. Among these requirements are:

The charge must be of uniform bulk-density. As used herein bulk-density is determined as follows:

$$\text{Bulk density} = \frac{\text{weight of sample}}{\text{volume of sample}}$$

The various sizes of the particles must be uniformly distributed within the charge.

The top surface of the charge must be maintained uniformly level in each canister.

The above conditions must be maintained in a charge that only partially fills the canister, or receptacle, to a predetermined depth therein.

The feeding of mixed-sized granular particles has been described in U. S. Patent No. 2,332,512, issued October 26, 1943, jointly to John C. Goshorn and the applicant. The present application

2

is an improvement on the apparatus described therein, that provides a novel automatic filling machine, and, in addition to other improvements, provides novel means for maintaining a uniform level surface of the charge.

As shown in the drawings, particularly in Fig. 1, the machine 10 includes vertical supports 11, and horizontal supports 12, 13, and 15. The motor drive assembly at 20, the turntable assembly at 40, the drop tubes at 52, and the hopper feed assembly at 60 are arranged thereon in cooperating relationship as shown in Fig. 1.

The motor drive assembly 20 includes a source of electric current, indicated at 32, and a conduit

15 31 to motor 21 which drives through belt 26 a well known variable pitch pulley unit at 25. The pivoted tilting arm 23 is adjusted by handle 29 on adjustable nut unit at 24. Drive pulley 27 through belt 30 drives driven pulley 28 on shaft

20 10 in reducing gear unit 33. Unit 33 drives turntable driving pinion 34 held on shaft 71 by hub attachment 39. Pinion 34 drives turntable driven gear 35 which is fixed to the vertical main shaft 36 by hub attachment means at 38.

Turntable assembly 40 includes housing 41, base plate 80, cam rail 43, chuck gear 49, and collar 42, all held in fixed relationship to support

15 13. Shaft 36 passes through collar 42 and rotates in collar 42. Turntable 48 is attached to

25 shaft 36 by means of hub collar 82.

Chucks 44 include chuck pinions 50 held on table 48 in operating engagement with chuck gear 49, by brackets 46 and bolts 47. Chuck pinions 50 are fixed to and rotate chuck shaft 83. Chuck rollers 45 freely rotate in chuck journal members

35 84, which are held in vertically sliding engagement with chuck sleeves 85. Chuck shafts 83

rotate chucks 44 in sleeves 85. Chucks 44 carry

and rotate containers or canisters by any suitable

engaging or slidably interfitting means.

40 Tubes 52 preferably include, for accessibility, a telescoping top member 53 lockable by means of pin 55 and slot 54. They are held by bottom plate

56 and top plate 57 which rotate with shaft 36

and table 48.

45 Hopper assembly 60 includes housing 61, which contains the annular compartment indicated in Fig. 1 by the walls shown in cross-section at 90 and 91. Hoppers 37 are mounted on plate 57, between compartmental walls 90 and 91, and each

50 held in alignment with its tube 52. Each hopper has a horizontal slide valve 67 having a discharge orifice 63 preferably somewhat greater in diameter than the discharge orifices 86 of hoppers 37.

A supply tube 62 is preferably positioned so that

55 it extends downwardly below the upper edges of

annular walls 90 and 91. It is arranged to readily control a constant supply of granular material to hoppers 37.

Slide valve 67 is mounted for horizontal reciprocating radial movement and is actuated by means of roller 58 held on slide 67 by axle shaft 59. The lower ends of tubes 52 are preferably provided with filling shields 68 which are positioned to extend downwardly through plate 56 and around the outside top edge portion of the container or canister when held in its upper filling position by chuck 44 on cam rail 43. The upper or filling position of chucks 44 is illustrated by the two outer chucks 44 in Fig. 1, and the lower or delivery position thereof by the chuck 44 indicated in its front central position in Fig. 1.

Horizontally fixed to support 11 is circular hopper cam rail 14, and positioned in operating relationship with slide roller 58. Adjustably held on rail 14, as shown in Fig. 1, is cam 95 which is positioned to move slide 67 when cam 95 rides in contact with roller 58. Cam 95 is arranged to be selectively positioned on the periphery of rail 14 in the path of roller 58 and acts to push slide 67 into its closed position so that its orifice 63 is entirely out of register with orifice 66 of hoppers 37.

Cam 66 is preferably fixed to circular rail 14 and positioned in the path of roller 58 so that it will act to push slide 67 into its open position, so that material will flow therethrough. Cam 66 is preferably provided with lever 65, which is arranged to pivot cam 66 out of the path of roller 58 when the machine is not in operation. Cam 95 is positioned at a sufficient distance on rail 14 from cam 66 so that slide 67 will remain in its open position for the length of time predetermined for filling a given container with the material selected. In Example 1 this time is 21 seconds.

The vertical central shaft 36 is preferably driven at approximately 2 R. P. M. This speed can be adjusted by variable pitch pulley unit at 23, or by changing gear reduction box at 33.

Example 1.—When filling a gas mask canister of 10.5 cm. inside diameter to a depth of 2.88 cm. with 250 ml. of charcoal granules having a bulk density of .65 gram per milli-litre, in order to obtain the optimum in level-surface filling it is necessary to rotate the container so that at least one revolution is obtained during the filling cycle, which requires 21 seconds. The container can not be rotated faster than 40 R. P. M. or the charcoal bed becomes dished, or thicker at the outer edge of the container, due to the action of centrifugal force. In practice, the container is preferably rotated 2.52 times during the filling cycle.

Fig. 2 shows in detail the arrangement of orifices 63 and 66, roller 58 and slide 67, and shield 68. It also shows the arrangement of screens 64, described in the patent previously referred to herein.

In order to determine the peripheral distance on rail 14 from cam 66 that cam 95 should be positioned, it is first desirable to determine a number of factors. Among these are:

1. Size and characteristics of granules.
2. Bulk density of charge.
3. Diameter of container.
4. Depth to which container is to be filled.
5. Mesh of screens.
6. Drop altitude of granules in tubes 52.

In general, the R. P. M. of chucks 44 should be low enough for even distribution of the granules

without any centrifugal action thereon. The R. P. M. should be high enough to maintain uniform level surface of the charge in the container without any centrifugal action on the granules.

Operation

In operation, the operator applies current at 32, and places the canisters or containers on chucks 44, as chucks 44 are lowered by cam 43 into the delivery and loading position. The rotation of shaft 36 moves rollers 58 into contact with opening cam 66, which opens slide 67 and permits the granular material to flow through hoppers 37, orifices 63 and 66, screens 64, and tubes 52, into the containers held by chucks 44 in their filling positions within shields 68.

In the example given, cam 95 is set to permit slide 67 to remain open for 21 seconds. At the end of that time roller 58 has moved into contact with cam 95, which closes slide 67. As this 21 seconds is ending the first of the six chucks 44 carrying the six containers is riding into the low position on cam ring 43. This lowers chuck 44, which in turn lowers the container below shield 68 so that the filled container can be removed by the operator, and replaced by an empty container on chuck 44. In this manner it will be seen that during approximately 21 seconds five of the six containers carried by the machine of the type illustrated in Fig. 1 are in the filling cycle at all times.

The foregoing drawings and specification illustrate one preferred embodiment of the present invention which is not intended to be limited thereto. It contemplates all embodiments and modifications within the spirit and scope of the appended claims.

I claim:

40. 1. Apparatus adapted to deliver leveled off uniform charges of granular materials into a plurality of individually rotating containers revolving in a common orbit, said apparatus including an upright frame having rigidly connected thereto in its upper portion a circular guide rail provided with spaced apart adjustably mounted cam members and having a vertical shaft centrally mounted in said frame and on a lower portion of said shaft a chuck ring gear and a circular cam rail provided with an upper cam surface and a lower cam surface, said shaft carrying in its upper portion and at a common distance from its vertical center line a plurality of equally spaced apart granular material hoppers provided with discharge outlets having slideable valve means adapted to successively open and close said outlets as the valve means moves against said guide rail, said shaft also carrying beneath said hoppers a plurality of elongated vertical granular material feed tubes in vertical registration with the discharge outlets of said hoppers and having beneath said tubes a circular turntable provided in its circumferential portion with a plurality of slidably and rotatably mounted chuck members in meshed engagement with said ring gear and in vertical alignment with said tubes, each of said chuck members being adapted to hold and slowly rotate one of said containers in vertical alignment with the longitudinal center line of the container and the axis of rotation of the chuck member and beneath one of said tubes, each of said chuck members being also in operative contact with said cam rail in a manner whereby said chuck members are
- 45.
- 50.
- 55.
- 60.
- 65.
- 70.

successively raised and lowered during each complete rotation of said shaft.

2. The apparatus of claim 1 in which said hoppers are carried in an annular hopper assembly having concentric wall portions higher than said hoppers adapted to receive the lower end of a downwardly depending granular material discharge tube between said wall portions for the purpose of preventing the granular material discharged above said hoppers from falling between said feed tubes.

3. The apparatus of claim 1 in which said granular feed tubes are provided with telescopic extensions adapted to be detachably secured to the lower end portions of said hoppers. 15
